UNITED STATES PATENT OFFICE.

WILLIAM L. CURRY, OF PITTSBURGH, PENNSYLVANIA; ALBERT CURRY AND COLONIAL TRUST COMPANY, OF PITTSBURGH, ADMINISTRATORS OF SAID WILLIAM L. CURRY, DECEASED.

APPARATUS FOR CONTROLLING THE COMBUSTION OF FUEL.

Application filed August 30, 1920. Serial No. 407,015.

To all whom it may concern:

Be it known that I, WILLIAM L. CURRY, a citizen of the United States, residing at Pittsburgh, in the county of Allegheny and State of Pennsylvania, have invented certain new and useful Improvements in Apparatus for Controlling the Combustion of Fuel, of which the following is a specification.

10 This invention relates to new and improved apparatus for controlling combustion of fuel in the generation of steam, and more particularly to apparatus for controlling the fuel feed, the air supply, and the escape of the products of combustion and waste gases by and in accordance with the flow and pressure variation in the steam outlet of a boiler.

15 I am aware that it has been proposed to regulate the combustion in furnaces by and in accordance with the method above mentioned, but so far as I am aware, prior to my invention, no apparatus capable of carrying out said method has been devised.

20 25 This invention should be distinguished from that class of inventions in which it has been the practice to regulate combustion by and in accordance with the pressure of the steam in the boilers or gases in the combustion chamber, or both.

30 The prime object of the present invention is to provide new and improved direct and positively operating apparatus of simple and efficient construction designed to be utilized in connection with regulating mechanism, means controlling the admission of air to a furnace and the escape of waste gases therefrom, and a fuel feeding device.

35 In the accompanying drawings, which illustrate an application of my invention,

40 Fig. 1 is a diagrammatic elevational view showing a furnace, boiler, etc., regulating apparatus, and operative connections embodying my invention; and

45 Fig. 2, a detail perspective view particularly showing a portion of the rigid connecting means employed.

50 Referring to the drawings, 2 designates a furnace construction of any desired type; 3, the combustion chamber; 4, a suitable fuel feed device; 5, the boiler; and 6, a steam or other vapor outlet pipe through which the vapor passes from the boiler to an engine. Air under pressure is introduced under the

furnace grate through an air conduit 7, and the exhaust gases pass from the furnace to a stack flue 8; and for the purpose of controlling the admission of air to the furnace and the passage of products of combustion and waste gases from the furnace, dampers 9 and 10 are provided.

55 As illustrated, suitable means are employed for regulating the dampers or valves 9 and 10 and the fuel feed device 4, said means, as hereinafter described, being operated by and in accordance with the variations in the rate of flow of vapor through the outlet, and by and in accordance with the vapor pressure therein.

60 Various forms of regulating apparatus 70 capable of use for carrying out the method of controlling combustion, as described herein, may be employed, and such apparatus per se is not my invention. The regulator mechanism shown includes a cylinder 12 75 having piston 13^a therein and its piston stem or rod 13 projecting above and below the cylinder and connected with a frame including top and bottom cross-heads 14. This frame is adapted to move with the piston and its stem 13, and the flow of fluid to the respective ends of this cylinder is controlled by a valve, not shown.

70 The regulator mechanism, in addition to the parts mentioned, includes an apparatus 85 or part 15 of any known or preferred construction which is subjected to variations in flow and pressure, said part 15 being in communication with the vapor outlet 6 by means of pipe 16, the device shown being one of a 90 well known type now in commercial use, the drawing representing a regulating mechanism of the type manufactured and installed by the Hagan Corporation, combustion engineers of Pittsburgh, Pennsylvania. Part 95 15 includes diaphragm mechanism, not shown, a weighted arm 17 movable by the diaphragm, an elongated fluid chamber 18 in which air or other compressible fluid at a predetermined pressure is confined, and operative mechanism between arm 17 and the diaphragm or diaphragms. The weights on arm 17 are adjusted to the normal requirements of the steam generator and to the pressure of the confined fluid in chamber 18. Means, not shown, are provided between the arm 17 and the valve controlling the flow of fluid to the respective sides of

the piston of cylinder 12. As the device 15 is designed to be operated by variations in the rate of flow of the fluid through pipe 6 and responsive to variations in pressure, some means involving the Pitot tube principle is employed in the pipe 6 for communicating dynamic pressure to the device 15 through pipe 16. For this purpose, I have shown specifically an orifice plate 18 in the pipe 6 and the pipe 16 communicates with the pipe 6 at a point immediately in the rear of this plate on the outlet side thereof. With the pipe 16 located at this point, an increase in the flow of fluid through the pipe 6 will increase the dynamic pressure and have the effect of lowering the static pressure communicated to the device 15 through pipe 16.

On the other hand, a decrease in the rate of flow of fluid through pipe 6 will have the same effect as an increase in the static pressure in the boiler. Consequently, the device 15 is responsive to variations in the rate of flow and in the pressure obtaining within the boiler. This is a condition to be desired because an increase in the rate of flow demands an increase in the heat applied to the boiler, while a decrease in the rate of flow, corresponding to an increase in the static pressure, demands that less heat be applied to the boiler.

A variation in the rate of flow of steam or other vapor in the outlet pipe 6 will cause the weighted arm 17 to be moved up or down thereby, through the means stated, admitting fluid to the upper or lower end of the cylinder 12 for the purpose of moving the piston-stem 13 up or down.

19 designates a regulating valve device in communication with the outlet pipe 6 through pipe 20, and with the engine of the fuel feeding apparatus 4 by means of pipe 21. The function of the regulating valve 19 is to control the steam passed to the stoker engine of the feed device 4, and the said regulating means in turn is controlled by the regulating mechanism above described.

The means connecting the regulator mechanism with the air controlling damper 9, the damper 10 controlling the escape of products of combustion, etc. from the furnace, and the valve device 19, constitute a characteristic and important feature of my invention. These means, as illustrated and as preferred, comprise a suspended frame formed of rigid members including an upper cross-head member 22 pivotally mounted on an end of a rotatable shaft 23, a lower cross-member 24 pivotally mounted on a similar shaft 25, and rigid vertically extending members 26 and 27, pivotally connecting the said cross-heads or members 22 and 24.

Rotatable shafts 23 and 25 project from a suitable support, not shown, and in addition to respectively carrying the said cross-mem-

bers 22 and 24, carry depending members 28 and 29, the latter being fixedly secured by a collar 30 to the respective shafts. Members 26 are connected with the lower and upper ends of the piston rod 13 of the regulator mechanism. It will be understood that a movement of the piston rod 13 will shift or rock the frame and that the movement of said frame will, through the means connecting the frame and the respective dampers and the regulating valve, move the said dampers and valve. As shown, damper 10 is provided with an arm 10^a, the latter being designed to be connected with the link or member 28 by means of a rod 31. Damper 9 is provided with an arm 9^a and said arm is connected with member 29 by a rod 32, bell crank lever 33, and rod 34.

Regulating valve device 19 includes an angle arm 35 and this arm is connected with the vertically extending rod 27 of the rock frame by pivotally connected rods or members 36 and 37.

What I claim is:

1. The combination with a steam generator and a furnace, of a steam outlet passage for the generator, a fluid pressure regulator communicating with said passage and responsive to pressure conditions therein, a suspended rocking frame comprising pivoted levers having corresponding ends connected with a movable part of the regulator through vertical rigid links and having their opposite ends connected by a link parallel with the vertical links, a damper, and means including cranks and links connected with said rocking frame for moving the damper.

2. The combination with a steam generator and a furnace, of a steam outlet passage for the generator, a fluid pressure regulator communicating with said passage and responsive to pressure conditions therein, a suspended rocking frame comprising pivoted levers having corresponding ends connected with a movable part of the regulator through vertical rigid links and having their opposite ends connected by a link parallel with the vertical links, a flue damper for the furnace, an air supply damper for the furnace, and rigid operating connections between the dampers and suspended rocking frame for moving the dampers according to the movement of the regulator.

3. The combination with a steam generator and a furnace, of a steam outlet passage for the generator, a fluid pressure regulator communicating with said passage and responsive to pressure conditions therein, a suspended rocking frame comprising pivoted levers having corresponding ends connected with a movable part of the regulator through vertical rigid links and having their opposite ends connected by a link parallel with the vertical links, a flue damper

for the furnace, an air supply damper for the furnace, a fuel feed control member for the furnace, and rigid operating connections between the rocking frame and said dampers, and fuel feed control mechanism for controlling combustion in the furnace according to pressure conditions in said steam outlet passage.

- 5 4. The combination with a steam generator and furnace for heating same having air supply means and a means for leading away waste gases, with a damper for controlling the air supply and a damper for controlling the waste gas escape, of an outlet for said steam generator, a pressure responsive device connected with said outlet and actuated in accordance with the rate of flow of steam from the generator, an operating device controlled by said pressure responsive means including a reciprocable element, a lower shaft connected with said reciprocable element and arranged to be rocked thereby, an upper shaft connected with said reciprocable element and rocked 45 by the movement thereof, a rigid connection between said lower shaft and said air supply damper to effect the operation of said damper when said lower shaft is rocked, rigid connection between the upper shaft 50 and said waste gas controlling damper to effect operation thereof when the upper shaft is rocked, said upper and lower shafts being operated in unison by said reciprocable element, an automatic fuel feeding 55 means, a controlling device therefor, and a rigid link connection between said device and said upper and lower shafts for operating said control means in accordance with the movement of said reciprocable element. 60
- 25 5. The combination with a steam generator and furnace for heating same having

air supply means and a means for leading away waste gases, with a damper for controlling the air supply and a damper for controlling the waste gas escape, of an outlet for said steam generator, a pressure responsive device connected with said outlet and actuated in accordance with the rate of flow of steam from the generator, an operating device controlled by said pressure responsive means including a reciprocable element, a lower shaft connected with said reciprocable element and arranged to be rocked thereby, an upper shaft connected with said reciprocable element and rocked 45 by the movement thereof, a rigid connection between said lower shaft and said air supply damper to effect the operation of said damper when said lower shaft is rocked, rigid connection between the upper shaft 50 and said waste gas controlling damper to effect operation thereof when the upper shaft is rocked, said upper and lower shafts being operated in unison by said reciprocable element, an automatic fuel feeding 55 means, a controlling device therefor, and a rigid link connection between said device and said upper and lower shafts for operating said control means in accordance with the movement of said reciprocable element. 60

In testimony whereof I affix my signature in presence of two witnesses.

WILLIAM L. CURRY.
